UNITED STATES PATENT OFFICE.

CHRISTAIN G. HUNT, OF DUNELLEN, AND JOHN H. COYLE, OF PLAINFIELD, NEW JERSEY.

ELECTRIC GAS-DETECTING SAFETY-LAMP.

1,294,806.

Specification of Letters Patent. Patented Feb. 18, 1919.

Application filed September 27, 1916. Serial No. 122,372.

To all whom it may concern:

Be it known that we, CHRISTAIN G. HUNT and JOHN H. COYLE, both citizens of the United States, residing, respectively, in 5 Dunellen, county of Middlesex, and State of New Jersey, and in Plainfield, county of Union, and State of New Jersey, have invented a new and useful Improvement in Electric Gas-Detecting Safety-Lamps, of 10 which the following is a description.

This invention relates to safety lamps, and particularly to a combination electric lamp and gas detector for mines, submarines, chemical plants, garages, dyeing 15 houses, gas chambers, etc.

Among the objects of our invention may be noted the following: to provide a means for detecting the presence of gas in mines, chambers, rooms, and other places, and 20 warning of the presence of certain explosive gases; to provide a lamp for use by miners, and others who are liable to be subjected to noxious gases, which will detect the presence of the gas in the immediate vicinity 25 and produce a signal indicating the fact; to provide an electric lamp so constructed that it will be immediately extinguished in the presence of an explosion, shock, or jar of sufficient severity to cause the breaking of 30 the lamp bulb or globe; to provide an electric lamp which must be perfect in all its fittings, connections and elemental structures before it can be made to burn for light-giving purposes and which, in the event any 35 of its parts becomes disconnected, loosened or opened, will cease burning, thus providing means for keeping the lamp in perfect working condition; and to provide a simple, durable and effective gas detecting electric 40 lamp for the uses and purposes above set forth, which is automatic in operation and can be set or regulated to produce several different effects as hereinafter described.

With the above objects in view and others 45 which will be detailed during the course of this description, our invention consists in the parts, features, elements and combinations thereof hereinafter described and claimed.

50 In order that our invention may be clearly understood, we have provided drawings wherein:

Figure 1 is a vertical central section of our combination electric lamp and gas de- 55 tector;

Fig. 2 is a plan view and partial section of the lamp-bowl;

Fig. 3 is an elevation of the structure of Fig. 2;

Fig. 4 is a section substantially on the 60 line 4—4 of Fig. 2;

Fig. 5 is a bottom plan view of a portion of the gas detecting and rheostatic mechanism;

Fig. 6 is a sectional plan of a portion of 65 said apparatus;

Fig. 7 is a side elevation of the structure shown in Fig. 5; and

Fig. 8 is a section substantially on the 70 line 8—8 of Fig. 5.

Referring to the drawings, the numeral 1 indicates a "Condulet" receptacle forming the base of the apparatus, the same being preferably substantially circular in form and provided with one or more conduit couplings 2 in which a section 3 of a tubular conduit may be screwed or otherwise securely fastened. An inner conduit 4, if desired, may be used through which are led the wires connecting with the feed 75 wires or mains, running from a service station, or generator, battery or other suitable current-producing means. The supporting base for any desired depth may be provided with insulating material 6, acting also as a 80 seal against moisture, dampness, etc., and which will surround and seal the inlet of the conduits 3 and 4, and in which also the connecting wires may be buried for protection and insulation. At its top, the base 85 1 may be closed by the bowl 6 of the lamp, which is provided with a lateral flange 7 and rim 8. The flange 7 may be bolted or otherwise detachably or permanently secured to the top of the base 1, and the bottom of the bowl 6 may be provided with a plate or closure 9 secured in place by screws 10, or other suitable means and providing a support for binding-posts 11, 11^a or other 90 suitable wire terminals. The top of the 100 base, through medium of the bowl 6, is hermetically sealed against gas and moisture by any suitable insulating compound 12 poured or molded into the bowl and filling the same to any extent desired; and 105 said compound may hold in place a non-conducting base or support 13 of any suitable form for supporting the usual screw-socket 14 for an incandescent lamp-bulb. The base 1 has secured to its top, directly 110

under the bottom of the bowl 6, a supporting disk 15, of insulating material the connection being made by lugs 16 and screws 17, or any other means found suitable. The 5 disk 15 is provided with a supporting bracket 18, in which the spindle 19, is clamped by nuts 20, the spindle being part of an expansible duplex diaphragm 21-22 having projecting therefrom the spindle 23, 10 the outer end of which is pivotally connected to a lever 24, fulcrumed at 25 to a supporting bracket 26, secured to the disk 15, said lever 24 carrying at its outer end a segmental rack 27, coöperating with a 15 pinion 28, also journaled in said bracket 26. A fine coiled spring 29 is connected at one end to the bracket 26 and at its other end to the spindle of the pinion 28, the tension of said spring normally tending to turn the 20 pinion against the action of the segment 27. Thus contraction and expansion of the diaphragm 21-22 will operate the spindle 23, lever 24 and pinion 28, the latter having secured to its spindle, at its lower end, the 25 long crank arm 30 adapted to coöperate with the series of contacts 31, connected by the series of resistance coils 32. Operation of the arm across the several contacts 31 will insert more or less resistance in the electric 30 circuit, resulting in increasing or decreasing the voltage translated to the electric lamp for the purpose presently described.

The chamber in the base, in which the apparatus just described is suspended, is open 35 to the atmosphere through the port 33 similar to the coupling part 2, thus enabling the diaphragm 21-22 to be subjected to the influence of air, and of gas as distinguished from air, entering said chamber. Preferably, the members of the diaphragm 21-22 contain each a disk-spring 34 of any suitable 40 form and strength adapted normally to expand and hold the diaphragms in opposition to external pressure, thus making said diaphragms slow of action, though still highly 45 susceptible to the pressure necessarily imposed upon them by gas which may enter the chamber in the base.

By reference to Figs. 1 to 4, it will now be 50 understood that the chambers in the base and in the lamp are sealed from each other and insulated from each other by means of the plastic composition and support 12 and 13 and are connected only electrically for 55 operation. The chamber in the bowl 6 above the plastic composition 12 is connected with the outside atmosphere through the medium of an automatically closing valve 35, which 60 normally seals the chamber against admission of external atmosphere, but which, under sufficient pressure, may admit carbonic acid gas, the latter being forced into the chamber of the bowl under pressure sufficient to operate or compress the duplex 65 diaphragm 36, located at the opposite side

of said chamber and having its interior open to the atmosphere through the rim 8 of the bowl, as by the hollow spindle 37 set in said rim. A lug or extension 38, on one of the diaphragm members, normally engages a 70 spring 39, fixed at 40 upon the insulating support 41, and adapted to engage at its free end the contact member 42, fixed to the insulating support 43, said spring being normally held away from contact 42 by extension 38, and operating as a circuit maker and breaker. The socket 14 is provided with the central contact 44 electrically connected as by the strip 45, to the binding-post 46. Another binding-post 47 is connected to the 80 socket 14. An incandescent bulb 48 is screwed into the socket 14 in usual manner and said bulb is surrounded by the globe 49 of heavy glass or other suitable, strong, transparent material. The globe is screw-threaded into the rim 50, Fig. 1, and engages a gasket 51 to tightly seal the connection between the rim and globe, and said rim 50 is fixed to the rim 8 in any suitable manner, with an intervening gasket or insulating 90 material 52 for sealing the joint. A collar 53 is screw-threaded upon the rim 50 and said collar has rigidly secured to it a cage 54 made of strong metal wire which surrounds the globe 49 and protects the same 95 against breakage and accidental contact with surrounding objects.

Assuming a source of electrical energy either D. C. or A. C., such as a generator, battery or main feed-wires, and the 100 connection of the leads 55, 56 thereto, the said leads will be carried through the conduit 4, the lead 55, to the binding-post 11, carried by the plate 9 on the bottom of the bowl 6. Thus the current will be carried 105 from the binding-post 11, through lead 58, to the terminal 40 of the switch-spring 39 (shown open in Fig. 1) which, if in the position shown in Fig. 2, the diaphragm 36 being compressed by the internal gas pressure in bowl 6, will translate the current to the contact 42, and thence by lead 59 to the binding-post 46, connection 45, and contact 44, to the filament connection 60 of the incandescent lamp, and thence by the filament 110 connection 61 to the contact 47, lead 62, to the binding-post 11^a, carried by the plate 9 on the bottom of the bowl 6. A lead 64 in turn carries the current to some portion of frame 26 or arm 30, normally engaged with 115 contact 31, forming part of the rheostatic device shown in Figs. 1 and 5. The current is thus conveyed through more or less of the resistance 32, according to the position of the contact arm 30, and passes thence from 120 its terminal 65 to the lead 56, thus completing the circuit back to source. Obviously, if the switch 39 is open, as shown in Fig. 1, the current cannot pass, and there will be 125 no light in the bulb 48. On the other hand, 130

according to the amount of resistance inserted in the circuit at 32, assuming the switch 39 to be closed as in Fig. 2, the lamp will burn more or less brightly thus giving the signal of danger or safety. The chambers of the duplex diaphragm 21-22 are substantial vacuums, which results in causing atmospheric pressure to compress the springs 34 of said diaphragm and store energy therein, thus drawing the arm or spindle 23, so as to swing the lever 24 and cause its rack, coöperating with the pinion 28, to swing the arm 30 counter-clockwise into engagement with the outer terminal 31, of the resistance, see Fig. 5, causing the lamp to burn at full power. This action is against the tendency of the spring 29 to shift the arm 30 across the contacts of the resistance 32 to insert the maximum resistance. Consequently when a gas which is lighter than air enters the chamber of the base 1, through the inlet 33, and rapidly diffuses therein, pressure is decreased in the chamber of bowl 6 by driving air from said chamber and operates upon the duplex diaphragm 21-22 to allow it to expand, which action is aided by the contained springs 34, thus actuating the lever 24, aided by the spiral spring 29, and shifting the arm 30, clockwise from terminal 31 toward terminal 65 to insert more resistance in the circuit, causing the incandescent lamp to be dimmed. This warns the operator of the presence of gases lighter than air and that it is time to leave the place where he is working. The resistance inserted as above noted will be sufficient to dim the light to the extent necessary to give the warning and yet will enable the lamp to give sufficient light for the operator to see his way to safety. On the other hand, the gas under compression in the chamber of the bowl 6 of the lamp normally compresses the duplex diaphragm 36 against the atmospheric pressure at 37, thus causing engagement of the switch 39 with contact 42 to complete the circuit and cause the lamp to burn at full power. Should an explosion occur in some portion of the mine at a distance from a given operator, resulting in increased pressure externally of the lamp, or should undue pressure from any cause occur externally of the lamp, the duplex diaphragm 36 would be expanded against the internal gas pressure resulting in breaking the engagement of spring 39 with contact 42, thus momentarily putting out the light of the lamp. Also, should the pressure of gas within the chamber of the bowl 6 be unduly reduced, the light would be extinguished and the operator thus warned to put his lamp in operative condition, which he will do by going to a place of safety or station provided for the purpose. Should a shock or jar break the bulb of the lamp, the gas contained in the chamber would immediately

expand, reducing pressure upon the diaphragm 36, resulting in breaking the contact at 42, the gas operating immediately to snuff the light. Should a shock or jar break the globe, or should the latter become fractured sufficiently to reduce gas pressure in the bowl-chamber, switch 39 will be shifted, the circuit broken and the lamp extinguished. Thus it will be understood that, under all conditions which may be encountered in the places where the lamp is adapted for use, the operator will not only be warned of the presence of surrounding gases, which are lighter than air, but will also be warned of possible danger; and, if his lamp is not in proper working condition, or operative as a detector and signal, he will know the fact from its failure to burn and he will immediately seek a place of safety and correct the fault.

While our invention, as above described, is embodied in a portable apparatus, capable of being carried in the hand or strapped to the body in any suitable way, it may also be set upon the floor, in niches, chambers or otherwise supported in stationary manner, and it may also be set in fixed positions on the timbers, walls, roof or other portions of mines, rooms, chambers, galleries, etc., and connected to the source of power through the medium of feed wires or mains, any number of said apparatus being inserted in series in the circuit in multiple, or in series parallel, the arrangement being merely a matter of electromechanics.

Having thus described our invention, what we claim and desire to secure by Letters Patent is:

1. In combination, an electric safety lamp having a sealed chamber; a source of light in said chamber; and means adapted to be operated by gas pressure in said chamber for normally maintaining the light and to be operated by pressure external to said chamber to extinguish the light.

2. The combination, in an electric safety lamp, of a source of light; gas pressure means in the lamp for normally maintaining the light; and means operated by external gas pressure for dimming the light without affecting the operation of the gas pressure means.

3. The combination, in an electric safety lamp, of a source of light; a sealed gas chamber surrounding said source of light; and means within the chamber responsive to the internal pressure of the gas to normally maintain the light, and to operate to snuff the light should the gas pressure in the chamber be either reduced or overcome.

4. The combination, in an electric safety lamp, of a source of light; gas pressure means in the lamp for maintaining the light; means responsive to gas pressure for dimming the light; the latter means includ-

- ing an element variable in its action for varying the dimming effect upon the light.
5. A safety lamp comprising a source of light; a sealed gas chamber containing the source of light; means within the gas chamber normally acting to maintain the light; means communicating with the atmosphere through said chamber and adapted to operate upon the light maintaining means to put out the light; and means responsive to external gas pressure to vary the light power.
10. The combination, in an electric safety lamp, having a pressure chamber; a source of light in said chamber; means in said chamber operable by gas pressure to maintain the light, and operable by external atmospheric pressure to extinguish the light.
15. A danger signaling apparatus comprising a supporting structure containing a sealed chamber and a chamber open to the atmosphere; a source of light within the sealed chamber; means within said sealed chamber for maintaining or snuffing said light; and means within the open chamber for varying the power of said light.
20. 7. A danger signaling apparatus for use in the presence of noxious gases, comprising an electric circuit having terminals in the apparatus; a source of light inserted in the circuit; means including a switch between the terminals adapted to be operated automatically by variations in atmospheric pressure; and means inserted in the circuit, including a rheostatic device for varying the voltage across the terminals, adapted to be automatically operated in the presence of a noxious gas.
25. 8. A safety lamp comprising a base provided with a chamber open to the atmosphere, in combination with a member supported on the base and containing a sealed chamber; a source of light in one of the chambers; means for maintaining said source of light; and means in the other chamber operable by pressure for varying the power of the light.
30. 9. A safety lamp comprising a source of light; means for normally maintaining the light in the presence of a gas within the lamp; and means including a rheostat operating upon the source of light to vary the power thereof in the presence of a noxious gas.
35. 10. The combination, in an electric safety lamp, having a pressure chamber; a source of light in said chamber; means in said chamber operable by gas pressure to maintain the light, and operable by external atmospheric pressure to extinguish the light.
40. 11. The combination, in an electric safety lamp, of a source of light; and means responsive to confined gas under pressure and to external pressure for respectively maintaining and extinguishing the light.
45. 12. The combination, in an electric safety lamp, of a source of light; means responsive to confined gas under pressure and to external pressure for respectively maintaining and extinguishing the light; and means responsive to pressure of gas lighter than air for dimming the light.
50. 13. The combination, in an electric safety lamp, of a source of light; means responsive to confined gas under pressure and to external pressure for respectively maintaining and extinguishing the light; and means normally inactive under said external pressure, but responsive in the presence of a gas lighter than air to modify the action of the other responsive means.
55. 14. The combination, in an electric lamp having a pressure chamber and a chamber open to the atmosphere; means in the pressure chamber responsive to pressure therein and outside atmosphere to affect the lamp; and means in the open chamber responsive to differences in pressure to affect the lamp.
